Fig. 1

Fig. 2

Fig. 4

FIG. 1 is a side elevational view of a mixing bowl showing my new design;

FIG. 2 is a top plan view;

FIG. 3 is an elevational view from the left of FIG. 1; and

FIG. 4 is an elevational view from the right of FIG. 1.

The dash lines in FIGS. 3 and 4 indicate the path in which the ornamentation is applied.

The essential feature of the design resides in the particular surface ornamentation and its arrangement on the mixing bowl.

I claim:

The ornamental design for a mixing bowl or the like, as shown and described.
